Primary Examiner — Cathron C Brooks*Assistant Examiner* — Yolanda Robinson(74) *Attorney, Agent, or Firm* — Cantor Colburn LLP(57) **CLAIM**

I claim, the ornamental design for a laser device, as shown and described.

DESCRIPTION

FIG. 1 is a front perspective view of a laser device, showing my new design;

FIG. 2 is a first side perspective view thereof;

FIG. 3 is a second side perspective view thereof, taken opposite from that of FIG. 2;

FIG. 4 is a first side elevation view thereof;

FIG. 5 is a second side elevation view thereof, taken opposite from that of FIG. 4;

FIG. 6 is a side view thereof adjacent to a cover; and, FIG. 7 is a front perspective view thereof with the cover on the device.

Portions shown in broken lines form no part of the claimed design.
